UNITED STATES PATENT OFFICE

WALDO A. MAAS AND GERALD BASIL SYKES, OF LONDON, ENGLAND

BINDER FOR LOOSE-LEAF BOOKS AND LIKE ARTICLES

Original application filed December 6, 1927, Serial No. 238,033, and in Great Britain December 6, 1926.
Divided and this application filed June 26, 1928. Serial No. 288,488.

The invention relates to means for binding within a cover a plurality of separately detachable leaves or groups of leaves.

One object of the invention is to provide novel means for securely retaining detachable leaves within a binder in such a manner as to allow for readily inserting or removing leaves from the binder.

Another object of the invention is to provide flexible retaining means associated with the binder to which the leads may be secured in a readily detachable manner.

A further object of the invention is to provide novel means for securing a flexible retaining member in association with a binder.

Other objects of the invention include the provision of novel elements of the structure together with the interrelation of parts and the combination of elements, the whole forming a simple practical device, which will be cheap and easy to manufacture and which will be simple to manipulate.

One feature of the invention relates to the provision of a flexible retaining strip for association with a binder which is formed of a material especially designed to withstand rough usage and yet will remain flexible to facilitate the manipulation of the device.

Another feature of the invention relates to the provision of novel means for permanently securing a retaining strip to a binder cover which will be simple in construction and effective in operation.

Another feature of the invention relates to improved means for adjustably and detachably securing one or both ends of a retaining strip in association with a binder cover.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection

with the accompanying drawings forming a part thereof, in which

Fig. 1 is a plan view of a binder constructed in accordance with the present invention;

Fig. 2 is a section taken on the line 2—2 of Fig. 1; and

Fig. 3 is a section taken on the line 3—3 of Fig. 1.

Like reference characters denote like parts in the several figures of the drawings.

In the following description and in the claims parts will be identified by specific names for convenience but they are intended to be as generic in their application to similar parts as the art will permit.

This invention is a division of our co-pending application Serial No. 238,033, filed December 6, 1927, for binders for loose leaf books and like articles.

Referring to the drawings more in detail, a binder for detachable leaves is illustrated comprising a pair of sides 10 and 11 either one of which may be used for the front of the binder as may be most desired depending upon the users choice. The sides 10 and 11 are preferably connected by a flexible member 12 which is designed to form the back of the binder.

For detachably securing leaves within the binder, there is associated with the binder, in a manner as will hereinafter be described, one or more flexible securing tapes 15. The tapes 15 are preferably formed of parchment either real or artificial, thus forming a durable securing tape having the desired stiffness together with a flexibility lending to the ease of manipulation of the device.

The binder is provided with a pair of hingedly connected members 40 to which means for securing the retaining tapes 15 are secured whereby full freedom of movement of the sides 10 and 11 is allowed without movement of the tape 15 or the retaining means associated therewith. For adjustably and detachably securing the tapes 15 to members 40, retaining elements 45 are provided.

As best illustrated in Fig. 3, the retaining members 45 comprise strips, formed as illustrated, to provide bearing surfaces 46 between threaded retaining members 47. Suit-

able eyelets 48 are provided within the sides 10 and 11 on the members 40 through which the retaining members 47 pass. The internal flange portions 49 of the eyelets are adapted to form guiding means for the tapes 15. By adjusting the tension applied to the member 46 by adjusting the threaded members 47, the tape 15 may be held in its adjusted position between the surfaces 46 and the member 40.

In using the above described binder, tapes 15 are released from one of the retaining members by loosening screws 47 sufficiently to relieve the pressure thereon. The tapes are then pulled from engagement with retaining member 46 and may be threaded through the leaves or other material to be placed within the folder. After the leaves have been thus inserted, tapes 15 are again passed under retaining members 46 and are clamped by tightening screws 47.

Obviously the tapes may be adjusted to any length desired depending upon the size of the binder and the quantity of material placed therein. They may also be adjusted from both ends in order to centrally place the tapes if desired, or to provide any relative positions between the various parts which may be required. Screws 47 are preferably formed with a sufficiently wide slot to enable them to be operated by commonly available articles, such as a coin. This avoids the necessity of maintaining a screw driver at hand in order to operate the binder and permits the same to be readily adjusted.

By employing screw threaded members for bringing plates 46 into engagement with tapes 15 a sufficient amount of pressure may be obtained to positively clamp the tapes against the cover members without the use of specially treated or formed elements or roughened surfaces.

While certain novel features of the invention have been shown and described and are pointed out in the annexed claims, it will be understood that various omissions, substitutions and changes in the forms and details of the device illustrated and in its operation may be made by those skilled in the art without departing from the spirit of the invention.

What is claimed is:—

1. In combination with a loose leaf binder, a flexible element associated therewith and adapted to retain the leaves therein, a pressure plate cooperating with said flexible element, and means for bringing said pressure plate into firm engagement therewith, comprising a member carried by said binder and threaded into said pressure plate, said threaded element being provided with a wide slot to permit operation thereof by a coin.

2. A pressure plate for a loose leaf binder adapted to receive and secure a flexible tape, said plate comprising a central bearing por-

tion and a pair of threaded portions located on opposite sides thereof, and means cooperating with said threaded portions for adjustably securing said plate.

3. In a loose leaf binder, a pair of hinged cover members, a hinged connecting member associated therewith and adapted to receive a flexible tape, a retaining member secured to said connecting member, and means for securely clamping said tape between said retaining member and said connecting member, said retaining member comprising a dished central portion adapted to bear on said tape and screw threaded portions on opposite sides thereof adapted to receive clamping screws.

4. In a loose leaf binder, a pair of hinged cover members, a hinged connecting member associated therewith and adapted to receive a flexible tape, a retaining member secured to said connecting member, and means for securely clamping said tape between said retaining member and said connecting member, comprising threaded members carried by said connecting member and engaging said retaining member.

5. In a loose leaf binder, a flexible member for securing leaves therein, connecting members for connecting said flexible member to said binder, clamping means associated with each of said connecting members having threaded means in engagement therewith for adjustably securing said flexible member thereto, said clamping members comprising a pressure plate adapted to engage said flexible member, and screw means passing through said connecting members and threaded into said pressure members for adjustably securing the same.

In testimony whereof we have hereunto set our hands.

WALDO A. MAAS.
GERALD BASIL SYKES.
